CLAIM

The ornamental design for a taco tray, as shown and described.

DESCRIPTION

FIG. 1 is a top plan view of a taco tray showing our new design;

FIG. 2 is a bottom plan view thereof;

FIG. 3 is a front elevational view thereof; the rear elevational view is identical thereto;

FIG. 4 is a left end elevational view thereof; the right end elevational view is identical thereto; and

FIG. 5 is a transverse vertical sectional view thereof taken in the direction indicated on line 5—5 of FIG. 3.

FIG. 1

FIG. 2

FIG. 3

FIG. 4

FIG. 5
